LUBRICATOR

Albert Feucht, Garfield Heights, Ohio, assignor,
by mesne assignments, to Le Roi Company,
Milwaukee, Wis., a corporation of Wisconsin

Application January 31, 1944, Serial No. 520,461

7 Claims. (Cl. 184—55)

1

The present invention relates to devices for supplying liquid to an air or other compressible fluid line and, more particularly, to improvements in lubricators of the type adapted to be attached to the supply line of a fluid actuated tool or mechanism and supply lubricant to the fluid passing therethrough so that it may be conveyed thereby to the movable parts of the tool.

In prior art devices, the most advantageous construction employed for supplying lubricant to a rock drill or other pneumatically operated tool included the use of a fabric member to feed by capillary attraction the lubricant from the reservoir to the air line. The fabric member and its capillary feeding characteristics made it possible to supply the lubricant regardless of the position assumed by the reservoir of the lubricator. However, use of such fabric members is objectionable due to the different types of lubricants employed throughout different parts of the country some of which have a tendency to clog the fabric with the result that the tool is improperly lubricated.

It is, therefore, an important object of this invention to provide a novel and improved lubricator constructed in such a manner that a supply of lubricant will flow from the reservoir and commingle with the pressure fluid flowing to the drill or other tool regardless of the position assumed by the reservoir or the type of lubricant employed.

Another object of the invention is to provide a novel and improved lubricator or like device having the above characteristics which does not rely upon a fabric member and capillary attraction for supplying the lubricant to the pressure fluid in the line.

Another object of the invention is to provide a novel and improved lubricator or device of the character referred to in which the parts thereof are readily accessible for adjustment, inspection, and repair.

Other objects and advantages more or less ancillary to the foregoing reside in the specific construction and arrangement of the elements peculiar to this structure, as will become apparent from a more complete examination of this specification.

In the drawing which illustrates the invention:

Fig. 1 is a longitudinal sectional view of a lubricator embodying the features of the present invention.

Fig. 2 is a vertical sectional view taken substantially on line 2—2 of Fig. 1.

2

Fig. 3 is a detail sectional view taken substantially on line 3—3 of Fig. 1.

Fig. 4 is a longitudinal sectional view similar to Fig. 1 with the parts in another position.

Fig. 5 is a detail sectional view taken substantially on line 5—5 of Fig. 1.

Referring to the drawings for a more detailed description thereof, the lubricator generally designated by the reference numeral 8 is shown to include a tubular shaped double-walled casing having a central opening therethrough and comprising a pair of opposed casing sections 9 and 10, which are preferably threaded as indicated at 11 to permit the same to be conveniently connected or disconnected. The outer ends of these sections are provided with nipples 12 and 13, respectively, said nipples being internally threaded as indicated at 14 and 15 for attaching the casing in the air line. As is to be understood, in lubricators of this character the casing is attached in the line and is spaced a slight distance from the rock drill or other pneumatically operated tool, one end of the line being connected, for example, with the nipple 13 while the line leading from the lubricator to the tool is connected to the casing through the nipple 12. It is to be understood, however, that the device will function efficiently regardless of the position it assumes in the line.

Formed as an integral part of the casing section 9 and extending inwardly thereof is a tube 16, said tube, when the sections are united as indicated in Fig. 1, extending within the section 10 and forming the inner wall of the casing.

The area within the outer wall of the casing and surrounding the tube 16 forms a reservoir 17 for the lubricant which is supplied thereto through the opening 18 closed by means of the filler plug 19. The tube 16 is formed with a central bore

20 in axial alignment with the bores 21 and 22 leading from the nipples 12 and 13, respectively, whereby a conduit or central opening through the casing is provided for the pressure fluid used for operating the rock drill or other pneumatically operated tool.

The bore 21 communicates with a passageway 23 which extends transversely of the section 9, said passageway in turn communicating with the bore 20. Positioned within the passageway 23 there is a nozzle 24 which forms, in part a means whereby pressure fluid is conveyed into the reservoir 17 to exert a pressure on the lubricant therein. The upper end of the nozzle 24 is shaped to receive a valve plug 25 which is formed adjacent its bottom end with a

passageway 26 communicating with a vertical passageway 27 for a purpose to be hereinafter described. The valve plug 25 is adjustably mounted within the nozzle, access thereto being provided through the plug 28. Upon removal of said plug 28, a screw driver or similar tool can be positioned within a slot 29 in the top of the valve 25 to rotate the same for altering the position of the passageway 26 with respect to a passage 30, to be referred to presently, to control the amount of lubricant fed therethrough to the tool as is readily apparent from an inspection of Fig. 3 of the drawings. An eccentric groove 26' in the exterior of the valve 25 and having its greatest depth adjacent to the passageway 26, see Fig. 3, provides an extremely delicate or fine adjustment for controlling the amount of lubricant fed into the passageway 23.

The casing 8 including the tube 16 is formed with longitudinally extending passages 30 and 31, lubricant being conveyed through the passage 30 and pressure fluid through the passage 31. The passage 30 communicates with the passageway 26 while the passage 31 communicates with a counterbore 32 positioned beneath the nozzle 24. The nozzle 24 is formed with a pair of diverging passages 33 leading into a vertical passage 34, the latter communicating with the bore 32. Pressure fluid entering the bore 20 through the nipple 13 will travel around the nozzle and through the bore 21 to the tool. However, a portion of the fluid will travel through the passages 33, 34, and into the bore 32 from where it is conveyed into the passage 31 and into the reservoir 17 through an annular groove 35, said groove communicating with the passage 31 through the inlet 36. As will hereinafter appear, the lubricant within the reservoir 17 being under pressure is fed to the tool through the annular groove 37 which communicates with the passage 30 through the inlet 38 and from the passage 30 is admitted into the passageway 23 through the passages 26, 27, and outlet openings 39, where it commingles with the pressure fluid flowing through the bore 20 to lubricate the moving parts of the tool.

For distributing the pressure fluid within the reservoir 17 and for conveying lubricant from the reservoir, there is provided a pendulum shaped member 39 loosely mounted on the tube 16, said member being capable of rotary movement and longitudinal movement relative to said tube. Longitudinal movement of the member 39 is limited by its contact at one end with the flange 40 and at its other end with the flange 41, the flange 40 forming a part of the inwardly extending portion 42 of the nipple 13 which receives the inner end of the tube 16, said tube being sealed therein as indicated at 43. The flange 41 forms a part of the tube, and its primary purpose is to provide a stop for limiting longitudinal movement of the pendulum shaped member in one direction. The upper side that is, the side opposite from the center of gravity of the member 39 is formed with passages 44 and 45 which communicate with the annular groove 35, said passages being extensions of the tubular shaped members 46 and 47 suitably held in the member 39 and extending in opposite directions within the reservoir 17. The lower portion of the member 39 is formed with passages 48 and 49 which communicate with the annular groove 37, the passage 49 communicating with the tubular member 50, while the passage 48 communicates with the tubular member 51. Members 50 and 51 are supported in the lower section of the pendulum

member and are provided with enlarged ends 52 protected by means of foraminous disks 53. As is understood, pressure fluid is discharged into the reservoir 17 through one or the other tubes 46 and 47, and lubricant is conveyed to the tool through one or the other tubes 50 and 51.

The positioning of the tubes 46 and 47 within the member 39 is such that one or the other of said tubes will always be above the level of the lubricant regardless of the position assumed by the lubricator. Likewise, the tubes 50 and 51 are positioned in the member 39 so that one or the other of said tubes will always be submerged in the lubricant irrespective of how the lubricator 8 may turn or roll.

With the device in the position shown in Fig. 1, the tubes 46 and 47 are above the level of the lubricant while the tubes 50 and 51 are totally submerged. However, should the device be moved to a vertical or a nearly vertical position, one of the air tubes would be above the level of the lubricant, and that tube would be in position to convey pressure fluid to the reservoir, and one of the tubes 50 or 51 would be submerged in the lubricant which tube would be in position to convey lubricant to the machine.

As shown in Fig. 2 of the drawings, the member 39 is formed with a pair of openings 54 and 55, the opening 55 serving to convey lubricant around the tube 16 to facilitate movement of the member 39 and at the same time effect a seal between said member and the tube. By means of the opening 54, any leakage of pressure fluid from the annular groove 35 which would tend to travel along the periphery of the tube 16 will be discharged through the opening 54 into the reservoir. Should the pressure fluid enter the annular groove 37 through the port 38, it would interfere with the travel of the lubricant through the passage 30, and it is to prevent this mixture of the pressure fluid with the lubricant that the opening 54 is provided.

With this construction, it will be evident that the pressure fluid to be supplied to the apparatus 45 and conveyed by a hose line passes through the central opening of the casing comprising the nipples 12 and 13 and the bore 20 of the sleeve 16. If lubricant is in the reservoir 17 and the parts are as shown in Fig. 1 of the drawing, a portion 50 of the pressure fluid will flow through the passages 33 and 34 into the bore 32 and from the bore through the passage 31, inlet 36, and annular groove 35 into the passages 44 and 45 for discharge through the tubes 46 and 47. It will 55 be seen that the annular groove 35 communicates with both passages 44 and 45 so that the pressure fluid will be discharged through each of the tubes 46 and 47 placing the lubricant within the reservoir 17 under pressure. As a consequence, lubricant will flow through the tubes 50 and 51, passages 48 and 49, into the annular groove 37 and into the passage 30 through the inlet 38. From the passage 30 the lubricant is 60 conveyed to the passageway 26 of the valve 25 downwardly through the vertical passage 27 for discharge into the bore 23 through the outlets 39' leading from the passage 27. The lubricant discharged through the outlets 39' will 65 commingle with the pressure fluid passing through the bore 20 and thus be carried to the apparatus 70 for lubricating the moving parts thereof.

In Fig. 4 of the drawing, the pendulum shaped member 39 which also serves as a valve member has been shifted due to changing the position of the lubricator and is now in contact with the

flange 41, and it will be observed that in this position the air tube 48 has been cut off from the annular groove 35, and accordingly, air can only be discharged through the tube 47. Also, when in this position, the lubricant conveying tube 51 has been cut off from the annular groove 37 so that lubricant can only be discharged into the passage 30 through the tube 50. It is thought to be readily apparent that the position of these several parts will be reversed when the member 39 is in abutting relation with the flange 40.

From the foregoing, it is thought that the construction, operation, and many advantages of the herein described invention will be apparent to those skilled in the art without further description. The positioning of the lubricant pick-up tubes 50 and 51 makes the device operable to convey lubricant to the fluid passing through the central bore of the apparatus regardless of the position assumed by the device so long as there is a small quantity of lubricant in the reservoir. It is also possible to have the reservoir 17 nearly filled with the liquid without danger of its overflowing into the air discharge tubes 46 and 47, or of its being forced into the pressure fluid through the passages 33 by expansion of the air in the reservoir 17 when the pressure is shut off, etc.

Although the foregoing description is necessarily of a detailed character, in order to completely set forth the invention, it is to be understood that the specific terminology is not intended to be restrictive or confining, and it is to be further understood that various rearrangements of parts and modifications of structural detail may be resorted to without departing from the scope or spirit of the invention as herein claimed.

I claim:

1. In a device of the character described, a double-walled casing having a central opening therethrough and a liquid reservoir therein, a member supported for rotation about an axis extending longitudinally of said central opening through said casing, said member having its center of gravity located to one side of its axis of rotation, conduit means in the inner wall of said casing and said member communicating with said central opening in said casing and with said liquid reservoir above the level of the liquid therein regardless of the position of said casing, and separate conduit means in the inner wall of said casing and said member communicating with the central opening of said casing and with said liquid reservoir below the level of the liquid therein regardless of the position of said casing.

2. In a device of the character described, a double-walled casing member having a central opening therethrough and a liquid reservoir therein, a member located within said reservoir and encircling the inner wall of said casing, means for supporting said member for rotation about an axis extending longitudinally of said central opening through said casing, said member having its center of gravity located to one side of its axis of rotation, conduit means in the inner wall of said casing and said member communicating with said central opening and with said liquid reservoir above the level of the liquid therein for all positions of said casing, and separate conduit means in the inner wall of said casing and said member communicating with said central opening and with said liquid reservoir below the level of the liquid therein for all positions of said casing.

3. In a device of the character described, a

double-walled casing having a central opening therethrough and a liquid reservoir therein, a member supported for rotation about an axis extending longitudinally of said central opening through said casing, said member having its center of gravity located to one side of its axis of rotation, conduit means in the inner wall of said casing and said member communicating with said central opening and with opposite ends of said liquid reservoir at the side opposite to said center of gravity, conduit means in the inner wall of said casing and said member communicating with said central opening and opposite ends of said liquid reservoir at the same side as said center of gravity, and valve means automatically operable when said casing is rotated about an axis extending transversely of said central opening for closing the conduit means at the opposite side of said center of gravity communicating with the lower end of said liquid reservoir and for closing the conduit means at the same side as said center of gravity communicating with the upper end of said liquid reservoir.

4. In a device of the character described, a double-walled casing having a central opening therethrough and a liquid reservoir therein, a member located within said reservoir and encircling the inner wall of said casing, means for supporting said member for rotation about an axis extending longitudinally of said opening in said casing, said member having its center of gravity located to one side of its axis of rotation, conduit means in the inner wall of said casing and said member communicating with said central opening of said casing and opposite ends of said liquid reservoir at the side opposite to said center of gravity, conduit means in the inner wall of said casing and said member communicating with said central opening of said casing and with opposite ends of said liquid reservoir at the same side as said center of gravity, and valve means automatically operable when said casing is rotated about an axis extending transversely of said central opening for closing the conduit means at the opposite side of said center of gravity communicating with the lower end of said liquid reservoir and for closing the conduit means at the same side as said center of gravity communicating with the upper end of said liquid reservoir.

5. In a device of the character described, a double-walled casing having a central opening therethrough and a liquid reservoir therein, a member supported for rotation about an axis extending longitudinally of said central opening through said casing, said member having its center of gravity located to one side of its axis of rotation, conduit means in the inner wall of said casing and said member communicating with said central opening in said casing and with said liquid reservoir at the side opposite to said center of gravity and above the level of the liquid therein regardless of the position of said casing, separate conduit means in the inner wall of said casing and said member communicating with said central opening through said casing and said liquid reservoir at the same side as said center of gravity and below the level of the liquid therein in all positions of said casing, and manually operable valve means comprising a rotatable member having a groove of varying depth therein adapted to form a part of said last-named conduit means.

6. In a device of the character described, a double-walled casing having a central opening

therethrough and a liquid reservoir therein, a member encircling the inner wall of said casing and slidably and rotatably carried thereby, said member having its center of gravity located to one side of its axis of rotation, conduit means in the inner wall of said casing and said member communicating with said central opening and with opposite ends of said liquid reservoir at the side opposite to said center of gravity, and conduit means in the inner wall of said casing and said member communicating with said central opening and with opposite ends of said liquid reservoir at the same side as said center of gravity, said conduit means being so constructed and arranged that movement of said member longitudinally of said casing incident to rotation of said casing about an axis extending transversely of the central opening therethrough automatically closes the conduit means at the opposite side of said center of gravity communicating with the lower end of said liquid reservoir and the conduit means at the same side as said center of gravity communicating with the upper end of said liquid reservoir.

7. In a device of the character described, a tubular-shaped double-walled casing having a central opening therethrough and a liquid reservoir therein, a member encircling the inner wall of said casing and slidably and rotatably carried thereby, said member having its center of gravity located to one side of its axis of rotation, conduit means in the inner wall of said casing and said member communicating with said central opening of said casing and with opposite ends of said liquid reservoir at the side opposite to said

15

20

30

center of gravity, conduit means in the inner wall of said casing and said member communicating with said central opening of said casing and with opposite ends of said liquid reservoir at the same side as said center of gravity, and manually operable valve means comprising a member rotatably supported in said casing and having a groove of varying depth therein adapted to form a part of said last named conduit means for controlling the flow of liquid therethrough, said conduit means being so constructed and arranged that movement of said member longitudinally of said casing incident to rotation of said casing about an axis extending transversely of said central opening automatically closes the conduit means at the opposite side of said center of gravity communicating with the lower end of said liquid reservoir and the conduit means at the same side as said center of gravity communicating with the upper end of said liquid reservoir.
